UNITED STATES PATENT OFFICE.

JULIUS J. MILLER, OF ST. JOSEPH, MICHIGAN, ASSIGNOR, BY MESNE ASSIGNMENTS, TO
WIREBOUNDS PATENTS COMPANY, OF KITTERY, MAINE, A CORPORATION OF MAINE.

WIRE-BOUND-BOX-BLANK MACHINE.

1,324,462.

Specification of Letters Patent. Patented Dec. 9, 1919.

Application filed November 18, 1911. Serial No. 660,706.

To all whom it may concern:

Be it known that I, JULIUS J. MILLER, a citizen of the United States of America, and resident of St. Joseph, Berrien county, Michigan, have invented a certain new and useful Improvement in Wire-Bound-Box-Blank Machines, of which the following is a specification.

My invention relates to machinery for making wire-bound box-blanks of that kind, in which the sheet material for the box sides and binding wires are stapled to reinforcing cleats that extend along the side edges of the blank.

Generally stated, the object of my invention is to provide a novel and efficient machine for making box-blanks of this general character.

Special objects are to provide a machine that will partially or preliminarily fasten the sheet material to the cleats, whereby no spacing devices are necessary for separating the ends of the cleats; to provide a machine having automatic means for interrupting the stapling operation and for spacing between blanks; to provide a machine of this kind in which the spacing between the blanks is conjointly controlled by the cleats and the reciprocation of the staplers; and to provide certain details and combinations tending to increase the general efficiency of a machine of this particular character.

To the foregoing and other useful ends, my invention consists in matters hereinafter set forth and claimed.

In the accompanying drawings:

Figure 1 is a side elevation of a wire-bound box blank machine embodying my invention.

Fig. 2 is a plan of the said machine.

Fig. 3 is a transverse section on line 3—3 in Fig. 1.

Fig. 4 is a perspective of the box-blank made by said machine.

Fig. 5 is an enlarged detail sectional view, showing one of the staplers in side elevation.

Fig. 6 is a rear elevation of the stapler shown in Fig. 5.

Fig. 7 is an enlarged detail view of a portion of the mechanism shown in Figs. 5 and 6.

Fig. 8 is a similar view showing another portion of said mechanism.

Fig. 9 is an enlarged plan of one of the

stops for automatically spacing between blanks.

As thus illustrated, my invention comprises a base A upon which the two upright body frames B and C are supported in proper relation to each other. These frames have transverse cross bars or table members b and c that support the longitudinal and parallel guides D in which the cleats 1 of the blank slide along in end to end relation during the operation of the machine. The frame B has a stationary cross head or beam b' above the guides D, and the usual vertically reciprocating cross head b² above the said stationary beam. The staplers E are mounted on these cross heads b' and b², in the ordinary manner, and are of any suitable or well known character, being operated by the vertical reciprocation of the beam b², and each stapler having a feed device e for feeding the staple wire carried on rolls F at the top of the machine. Each staple wire feed device is operated by a pawl e' carried up and down by the cross head b² and controlled by a spring e². The binding wires 2 of the blanks are fed from reels G at the top of the frame, each stapler having suitable means for guiding the binding wire below the staple driver thereof, whereby the staples are inserted crosswise of the binding wire and through the sheets 3 of box side material and into the cleats 2 of each blank. The belt or belts H are arranged to support the cleats 2 in the guides D, being mounted to run on pulleys h on the frames B and C, and are operated at relatively high speed by any suitable transmission. The frame C has a rigid cross head or beam c', and a vertically reciprocating cross head c², which cross heads are common and readily understood, and like those of the other frame. Staplers I are mounted on the beam c' and operated by the cross head c², in the well known manner, and are disposed over the guides D, one at each side of the machine. Each stapler has a staple wire feed device i operated by a pawl i' carried on the cross head c², whereby the wire is fed from the reels i' at the top of the frame C, each wire being converted into staples in the well known manner. The cross heads b² and c² are actuated by the usual pitmen and eccentrics b³ and c³, which are operated by the drive shafts b⁴ and c⁴, said shafts being usual in machines for this

purpose. These shafts are driven in any suitable manner.

The guides D are provided with stops J that are located below and a little to the rear of the staplers I, each stop being mounted to slide up and down. These stops are suitably connected with a foot lever j, whereby depression of said lever operates to pull the stops downward and out of the path 10 of the cleats. A spring j' serves to keep the said stops normally raised and in the guides, whereby the cleats may be placed in the guides with their ends against said stops.

These stops are exactly opposite each other, 15 and while the cleats are thus held stationary, a body strip or sheet may be stapled by two staples to the cleats, preliminary to delivering these parts to the belts H. As shown the upper ends of the stops J are formed to 20 engage the ends of the cleats and permit the edge of the sheet to overhang the ends of the cleats. The sheet or body strip 3 is secured in place with its edge overhanging the ends of the cleats, and thus the four 25 sections of the blank are fed forward with their edges tightly together. The stops J may be formed, as shown in Fig. 1, of such profile as to provide means for the proper relative positioning of the sheet or body 30 strip and the cleats. The overhang of the sheets 3 serves to space the ends of the cleats apart, as the sheets and cleats are in this way partially and preliminarily secured together. When a sheet has been secured by 35 two staples, one at each end, or by more if necessary, the operator then depresses the stops J and pushes the blank section on to the belts H, whereby the sections are thus fed forward in the guides.

40 When the sections of the blanks pass under the staplers E, the binding wire is then secured in place, and the cleats and sheets are thereby fully secured together. The step-by-step feeding motion necessary for 45 permitting the staplers E to do their work is produced by the feeding mechanism K behind the said staplers. This feeding mechanism comprises a pair of endless link belts k having teeth that impinge upon the 50 upper surface of the wired portion of each blank. These chains are carried on sprockets k' on shafts k'', which shafts are given a step-by-step rotation by any suitable ratchet device or other means. In this way 55 the cleats and sheets cannot advance any faster than they are permitted by the mechanism K, notwithstanding the high speed of the belts H which keeps the sections of the blank crowded close together before 60 passing under the staplers E by which the binding wires are applied. Thus the overhanging edges of the veneer or sheets are used for spacing the cleats apart endwise, and no spacing devices are necessary.

65 Mechanism is also provided for automati-

cally spacing between the blanks, as follows: A bevel ended stop L projects into one guide D, at a point below and a little to the rear of the stapler E, and is connected with a lever l which is pivoted at l' and controlled by a spring l''. This stop L presents its beveled surface to the ends of the cleats, and the spring l'' is strong enough to resist the thrust of the belts H, but yields to the pull of the mechanism K, whereby the cleats 70 and body strips will remain stationary, each time, until one staple is driven in the cleat which is against the said stop, after which the pull of the binding wire thereby attached to this cleat serves to overcome the tension 75 of the spring l'' and push the stop L out of the way. A similar stop M is provided at the other side of the machine, to engage the other row of cleats, except that this stop does not need the lever l, but is merely a 80 spring operated and bevel-ended stop that holds each cleat stationary until the binding wire pulls it along. The lever l has a hook-shaped pawl l' at the upper end thereof, which pawl engages a ratchet wheel l'' 85 having only four teeth and a blank space. This wheel l'' is on a short shaft l' that extends horizontally through the beam b', and which carries a cam wheel l'' on the other end thereof. A horizontal rock-shaft N 90 runs across the back of the beam b', and is provided with fingers n for engaging the feed pawls e' to disengage the latter from the feed devices e when it is desired to stop the driving of the staples without stopping 95 the machine. The shaft N has an arm n' that engages the cam l'', whereby the said cam operates to rock the said shaft. The shaft l'' has, also, a ratchet wheel l'' having only three teeth and a blank space, said 100 wheel being engaged by a hook-shaped pawl l'' that is pivoted at its upper end to the cross head b'' and controlled by a spring l'', whereby the shaft l'' is rotated only by upward movement of said pawl. The stop L 105 moves in and out between the ends of the cleats, and this causes the lever l to operate the pawl l'' to rotate the shaft l'', this rotation occurring only four times, as there are only four teeth on the ratchet wheel l''. 110 These four actuations are sufficient, however, to bring the cam l'' into engagement with the arm n', thus automatically tripping out the staple wire feed upon the passage of the fourth cleat out of engagement 115 with the stop L. This stops the driving of the staples, but the pawl l'' now takes up the rotation of the shaft l''. As the wheel l'' has only three teeth, it follows that it requires three upward strokes of the cross head l'' to again bring the cam l'' out of engagement with the arm n', and to thus restore the staple wire feed devices to operative condition. During this time the wired 120 blank is moving along under the mechanism 125 130

K, but the unwired cleats and sheet material in front of the staplers remain stationary against the stops L and M. This is because during this time no staples are being driven; but upon the fourth stroke of the cross head the driving of staples is resumed, and then the operation of wiring the next blank proceeds as before. In this way the staple wire feed is automatically tripped out by the 10 passing of four cleats in front of the stop L; a space is formed between the blank, and then the idle reciprocation of the staplers while no staples are being driven is utilized to restore the wire feed to operative condition. In other words, the cleats and staplers 15 conjointly control the mechanism by which the spaces are produced between blanks.

Thus one person can tend the machine, if desired, as the manual manipulation of the 20 parts in front of the staplers L is all that is required. After this the operation is entirely automatic in character.

The element L operates as a stop to interrupt the feeding motion of the work and 25 thereby provide spaces at predetermined intervals therein. This, of course, is done without stopping the machine, except the driving of the staples is prevented during each interruption and while the space is being formed. As shown, the rolls e and pawls e' are devices for performing an operation 30 on wire, and in this case each device takes the form of a feeding device; but for the broader purposes of my invention, and so far as the automatic control of a device by an element which engages the passing or 35 moving materials is concerned, this feature of my invention may be used for any suitable purpose, and I do not limit myself to the particular constructions and uses shown 40 and described. The element L is operated as many times for each blank as there are sides for the box when completed, and in this case there are four of these operations 45 required to throw out the pawls e' of the wire feeding devices. It is obvious, however, that this number can be changed or varied to suit the conditions, without departing from the spirit of my invention.

50 What I claim as my invention is:

1. In machinery for making wire-bound and cleat reinforced box-blanks, mechanism comprising coöperating work feeding and fastener driving elements for securing the 55 binding wire and sheet material to the cleats, means to operate the said work feeding and fastener driving elements intermittently and alternately whereby the different sections of the blank are successively connected 60 together, means for preliminarily securing the sheet material to the cleats, and means disposed in position to deliver the sheet material and cleats to said mechanism.

2. In machinery for making wire-bound 65 and cleat reinforced box-blanks, mecha-

nism comprising coöperating work feeding and fastener driving elements for securing the binding wire and sheet material to the cleats, means to operate the said work feeding and fastener driving elements intermittently and alternately whereby the different sections of the blank are successively connected together, means for gaging the position of the sheet material and cleats and partially securing them together, and means disposed in position to deliver the sheet material and cleats to said mechanism. 70

3. In machinery for making wire-bound and cleat reinforced box-blanks, mechanism comprising coöperating work feeding and fastener driving elements for securing the binding wire and sheet material to the cleats, means to operate the said work feeding and fastener driving elements intermittently and alternately whereby the different sections 80 of the blank are successively connected together, means for preliminarily securing the sheet material to the cleats, with the edges of the sheet material overhanging the ends of the cleats, and means disposed in position to deliver the sheet material and cleats to said mechanism, said mechanism being provided with means for feeding the blanks with the ends of the cleats spaced apart only by the said overhanging edges of 85 the sheet material. 90

4. In machinery for making wire-bound and cleat reinforced box-blanks, mechanism comprising coöperating work feeding and fastener driving elements for securing the 100 binding wire and sheet material to the cleats, means to operate the said work feeding and fastener driving elements intermittently and alternately whereby the different sections of the blank are successively connected together, means for gaging the position of the sheet material and cleats and partially securing them together, with the edges of the sheet material overhanging the ends of the cleats, and means disposed in position to deliver the sheet material and cleats to said mechanism, said mechanism being provided with means for feeding the blanks with the 105 ends of the cleats spaced apart only by the said overhanging edges of the sheet material. 110

5. In machinery for making wire-bound and cleat reinforced box-blanks, mechanism comprising coöperating work feeding and fastener driving elements for securing the 120 binding wire and sheet material to the cleats, means to operate the said work feeding and fastener driving elements intermittently and alternately whereby the different sections of the blank are successively connected together, means for preliminarily securing the sheet material to the cleats, and means disposed in position to deliver the sheet material and cleats to said mechanism, said mechanism being provided with means for feed- 125 130

1. In machinery for making wire-bound and cleat reinforced box-blanks, mechanism comprising coöperating work feeding and fastener driving elements for securing the binding wire and sheet material to the cleats, means to operate the said work feeding and fastener driving elements intermittently and alternately whereby the different sections of the blank are successively connected together, means for preliminarily securing the sheet material to the cleats, disposed in position to deliver the sheet material and cleats to said mechanism, and means for automatically spacing the blanks apart. 65
2. In machinery for making wire-bound and cleat reinforced box-blanks, mechanism comprising coöperating work feeding and fastener driving elements for securing the binding wire and sheet material to the cleats, means to operate the said work feeding and fastener driving elements intermittently and alternately whereby the different sections of the blank are successively connected together, means for gaging the position of the sheet material and cleats and partially securing them together, and means disposed 70 in position to deliver the sheet material and cleats to said mechanism, said mechanism being provided with means for feeding the blanks with the sections thereof in contact with each other. 75
3. In machinery for making wire-bound and cleat reinforced box-blanks, mechanism comprising coöperating work feeding and fastener driving elements for securing the binding wire and sheet material to the cleats, means to operate the said work feeding and fastener driving elements intermittently and alternately whereby the different sections of the blank are successively connected together, means for gaging the position of the sheet material and cleats and preliminarily 80 securing them together, means disposed in position to receive and deliver the preliminarily fastened sheet material and cleats to said mechanism, and means for automatically spacing the blanks apart. 85
4. In machinery for making wire-bound and cleat reinforced box-blanks, mechanism comprising coöperating work feeding and fastener driving elements for securing the binding wire and sheet material to the cleats, means to operate the said work feeding and fastener driving elements intermittently and alternately whereby the different sections of the blank are successively connected together, means for gaging the position of the sheet material and cleats and preliminarily 90 securing them together, means disposed in position to receive and deliver the preliminarily fastened sheet material and cleats to said mechanism, and means for automatically spacing the blanks apart. 95
5. In machinery for making wire-bound and cleat reinforced box-blanks, mechanism comprising coöperating work feeding and fastener driving elements for securing the binding wire and sheet material to the cleats, means to operate the said work feeding and fastener driving elements intermittently and alternately whereby the different sections of the blank are successively connected together, means for preliminarily securing the sheet material to the cleats, disposed in position to deliver the sheet material and cleats to said mechanism, the said mechanism being provided with means for engaging the wired portions of the blanks to produce a step-by-step feeding movement thereof, and a relatively high speed friction feed arranged to receive the unwired and partially secured sheet material and cleats and advance them to said mechanism. 100
6. In machinery for making wire-bound and cleat reinforced box-blanks, mechanism comprising coöperating work feeding and fastener driving elements for securing the binding wire and body strips to the cleats, means to operate the said work feeding and fastener driving elements intermittently and alternately whereby the different sections of the blank are successively connected together, and means for gaging the position 105 of the sheet material and cleats and partially securing them together, disposed in position to deliver the sheet material and cleats to said mechanism, the said mechanism being provided with means for engaging the wired portions of the blanks to produce a step-by-step feeding movement thereof, and a relatively high speed friction feed arranged to receive the unwired and partially secured sheet material and cleats and advance them to said mechanism. 110
7. In machinery for making wire-bound and cleat reinforced box-blanks, mechanism comprising coöperating work feeding and fastener driving elements for securing the binding wire and sheet material to the cleats, means to operate the said work feeding and fastener driving elements intermittently and alternately whereby the different sections of the blank are successively connected together, means for preliminarily securing the sheet material to the cleats, means disposed in position to receive and deliver the preliminarily fastened sheet material and cleats to said mechanism, said fastener driving elements comprising a plurality of staplers each 115 having a device for feeding the wire for the staples, means controlled by the cleats for tripping out the said wire feed devices, to produce a space between two blanks, and means controlled by the staplers for tripping in the wire feed devices when the requisite space has been produced. 120
8. In machinery for making wire-bound and cleat reinforced box-blanks, mechanism comprising coöperating work feeding and fastener driving elements for securing the binding wire and sheet material to the cleats, means to operate the said work feeding and fastener driving elements intermittently and alternately whereby the different sections of the blank are successively connected together, means for gaging the position of the sheet material and cleats and preliminarily 125 securing them together, means disposed in position to receive and deliver the preliminarily fastened sheet material and cleats to said mechanism, said fastener driving elements comprising a plurality of staplers

- each having a device for feeding wire for the staples, means controlled by the cleats for tripping out the said wire feed devices, to produce a space between two blanks, and 5 means controlled by the staplers for tripping in the wire feed devices when the requisite space has been produced.
13. In machinery for making wire-bound and cleat reinforced box blanks, mechanism 10 for stapling the binding wire and sheet material to the cleats, and means controlled conjointly by the cleats and said stapling mechanism for automatically spacing between blanks.
14. In machinery for making wire-bound and cleat reinforced box-blanks, instrumentalities for feeding the materials, mechanism for stapling the binding wire and sheet material to the cleats, means to position the sheets on the cleats, and devices for automatically spacing between blanks, operating independently of said means, and controlled by direct engagement with the passing materials.
15. In a machine for making wire-bound and cleat-reinforced box blanks, mechanism for stapling the binding wire sheet material and cleats together, means to position the sheets on the cleats, and automatically controlled devices for spacing between blanks.
16. In a stapling machine, a staple forming and driving mechanism, a device for feeding the wire for the staples, mechanism controlled by the work for tripping out the said wire feed device, and means controlled by the continued motion of said staple-forming and driving mechanism for tripping in the said wire feed device, whereby an interval of no staple driving is produced without stopping the machine.
17. A wire bound box blank machine comprising instrumentalities for feeding materials and stapling the binding wires thereto, and means for automatically spacing between blanks, including an element which engages the materials to govern the operation of said means, said means having devices controlled by said element to prevent the driving of staples in the spaces between the blanks.
18. A box blank machine comprising instrumentalities for feeding materials and inserting fastening devices therein, and means for automatically interrupting the driving of the fastening devices, without 55 stopping the machine, including an element which directly engages the materials and is operated a plurality of times for each blank to govern the operation of said means.
19. A box blank machine organized for 60 wiring successive pieces of work,—which comprises, in combination, fastener-setting mechanism to secure binding wire to the materials; work-feeding means adapted for yieldingly advancing a succeeding toward
- a preceding piece of work; a member adapted to enter between the pieces of work and arrest the progress of the succeeding piece; and means for interrupting the fastener-setting operation during such arrest and for causing resumption of the fastener-setting 70 operation on the succeeding piece of work; the said element being yieldable to the pull by the binding wires on the succeeding piece of work; whereby the pieces of work are automatically spaced. 75
20. A box blank machine comprising a stapling mechanism having a wire feed, and means for automatically rendering said wire feed inoperative, to prevent the driving of staples without stopping the operation of 80 the stapling mechanism, including an element which engages the work and is displaced laterally thereby to govern the operation of said means.
21. A box blank machine comprising a 85 movable member which directly engages the blank materials and devices controlled by the actuation of said element a plurality of times by the materials of each blank to automatically govern the operation of the machine without stopping the same.
22. A box blank machine comprising a 90 stapler provided with a device for feeding the staple wire thereto, means to feed the blank materials forward, an element arranged to bear directly against the passing materials, and means operated by said element to control the operation of said device, said element being arranged to enter the path of the materials and periodically interrupt the feeding motion thereof. 95
23. A box blank machine comprising a 100 device for operating on wire, means to feed the blank materials forward, an element arranged to bear directly against the passing materials, and means operated by said element to control the operation of said device, said element being arranged to enter the path of the materials and periodically interrupt the feeding motion thereof. 105
24. A machine for making box blanks by 110 stapling sheets to cleats and wiring together the previously unconnected side sections of each blank, comprising mechanism to position the sheets relatively to the cleats, instrumentalities to fasten the sheets to the cleats, means to feed the fastened sheets and cleats forward, and devices for receiving the assembled sheets and cleats and applying binding wires to flexibly connect the sections 115 of the blank, said devices including staplers arranged to operate a plurality of times on each side section. 120
25. A machine for making box blanks by 125 stapling sheets to cleats and wiring together the previously unconnected side sections of each blank, comprising mechanism to position the sheets relatively to the cleats, in-

5. instrumentalities to fasten the sheets to the cleats, means to feed the fastened sheets and cleats forward, and devices for receiving the assembled sheets and cleats and applying binding wires to flexibly connect the sections of the blank, said devices including staplers arranged to operate a plurality of times on each side section, and said mechanism including stops disposed in the paths of the cleats, and means to withdraw said stops downward. 70
10. 26. A machine for making box blanks by stapling sheets to cleats and wiring together the previously unconnected side sections of each blank, comprising mechanism to position the sheets relatively to the cleats, instrumentalities to fasten the sheets to the cleats, means to feed the fastened sheets and cleats forward, and devices for receiving the assembled sheets and cleats and applying binding wires to flexibly connect the sections of the blank, said devices including staplers arranged to operate a plurality of times on each side section, and said means including belts which travel faster than the sheets and cleats. 80
15. 27. A machine for making box blanks by stapling sheets to cleats and wiring together the previously unconnected side sections of each blank, comprising mechanism to position the sheets relatively to the cleats, instrumentalities to fasten the sheets to the cleats, means to feed the fastened sheets and cleats forward, and devices for receiving the assembled sheets and cleats and applying binding wires to flexibly connect the sections of the blank, said devices including staplers arranged to operate a plurality of times on each side section, and said instrumentalities including staplers arranged to insert only a single staple in each cleat. 90
20. 28. A machine for making box blanks by stapling sheets to cleats and wiring together the previously unconnected side sections of each blank, comprising mechanism to position the sheets relatively to the cleats, instrumentalities to fasten the sheets to the cleats, means to feed the fastened sheets and cleats forward, and devices for receiving the assembled sheets and cleats and applying binding wires to flexibly connect the sections of the blank, said devices including staplers arranged to operate a plurality of times on each side section, and said mechanism including foot-controlled stops movable into and out of the paths of the cleats. 100
25. 29. A box blank machine comprising devices for feeding the blank materials forward, a ratchet mechanism, an element engaging the materials to actuate said mechanism as many times for each blank as there are sides thereof for the box, means controlled by said mechanism to interrupt the motion of the materials at predetermined intervals, without stopping said devices, and mechanism arranged to operate during each interruption to determine the duration thereof. 110
30. 30. A box blank machine comprising devices for feeding the blank materials forward, a ratchet mechanism, an element engaging the materials to actuate said mechanism as many times for each blank as there are sides thereof for the box, means controlled by said mechanism to interrupt the motion of the materials at predetermined intervals, without stopping said devices, and mechanism arranged to operate during each interruption to determine the duration thereof, said element being movable into and out of the path of the materials, thereby serving as a stop during the interruption to produce spaces between the blanks. 120
35. 31. A box blank machine comprising devices for feeding the blank materials forward, a ratchet mechanism, an element engaging the materials to actuate said mechanism as many times for each blank as there are sides thereof for the box, means controlled by said mechanism to interrupt the motion of the materials at predetermined intervals, without stopping said devices, and mechanism arranged to operate during each interruption to determine the duration thereof, said means including a device to prevent driving of staples during each interruption. 130
40. 32. A box blank machine comprising devices for feeding the blank materials forward, a ratchet mechanism, an element engaging the materials to actuate said mechanism as many times for each blank as there are sides thereof for the box, means controlled by said mechanism to interrupt the motion of the materials at predetermined intervals, without stopping said devices, and mechanism arranged to operate during each interruption to determine the duration thereof, said last mentioned mechanism including a ratchet device operable a plurality of times for each interruption. 140
45. 33. A box blank stapling machine comprising means for feeding the blank materials forward, a movable element disposed in position to engage and be operated by the passing materials, and devices controlled by said element to properly space the work at predetermined intervals therein, said element being arranged to enter the path of the materials and serve as a stop therefor during the formation of each space. 150
50. 34. A box blank stapling machine comprising means for feeding the blank materials forward, a movable element disposed in position to engage and be operated by

- the passing materials, and devices controlled by said element to properly space the work at predetermined intervals therein, said devices including means to prevent 5 the driving of staples during the formation of each space.
35. A box-blank machine for connecting box-blank sections fed in a definite path comprising a spacer movable into and out 10 of such path and immovable in the direction of feed.
36. In a machine for making box-blanks, feeding means for driving the material through the machine, stapling means, and 15 means controlled by the passage of a given plurality of units of the box-blank material temporarily to interrupt the action of the stapling means upon the box-blank material.
37. In a machine for making box-blanks, 20 a stapling means, means for guiding the box-blank material through the stapling plane, and means controlled by the passage of a given plurality of units of the box-blank material temporarily to interrupt the 25 action of the stapling means upon the box-blank material.
38. A box-blank machine comprising, in combination, mechanism to secure binding wires to the blank materials, means to feed 30 the parts operated on by said mechanism, and a member engaging said materials and movable under the force of said feeding means, and through such movement operating on the passage of a determined length of 35 blank to interrupt the securing action of said mechanism and by such interruption causing intermission of the passage of blank material under the action of said feeding means.
39. A box-blank machine comprising, in combination, mechanism to secure binding wires to the cleats and side material, means to feed the parts operated on by said mechanism, and a member extending into the path 45 of the cleats and yieldable therefrom under the force of said feeding means on the passage of each cleat, and through such yielding operating on the passage of a predetermined number of cleats to interrupt the securing 50 action of said mechanism and by such interruption causing intermission of the passage of blank material under the action of said feeding means.
40. A box-blank machine comprising, in combination, mechanism to secure binding wires to the cleats and side material, means to feed the parts operated on by said mechanism, and a member extending into the path of the cleats and yieldable therefrom 55 under the force of said feeding means on the passage of each cleat, and through such yielding operating on the passage of a predetermined number of cleats to interrupt the securing action of said mechanism and by
- such interruption causing intermission of the passage of blank material under the action of said feeding means, and an auxiliary means to feed blank material into contact with said member.
41. In a machine for making box-blanks, 70 feeding means for driving the box blank material through the machine, with the necessary spaces formed therein, stapling means, an element to engage the material, and means caused to operate by entrance 75 of said element into spaces occurring at intervals in the box-blank material to intermittently interrupt the action of the stapling means upon said material.
42. In a machine for making box-blanks, 80 stapling means, means for guiding the box-blank material through the stapling plane, with the necessary spaces formed therein, an element to engage the said material, and means caused to operate by entrance of said 85 element into spaces occurring at intervals in the box-blank material to intermittently interrupt the action of the stapling means upon said material.
43. A machine for use in making wire-bound boxes comprising, in combination, co-operating blank-feeding and wiring and fastener-setting instrumentalities, and operating means therefor, said elements constructed and arranged to provide a continuously-operating organization for wiring successive blanks without stopping the machine, and automatic means for interrupting the fastener-setting operation in the 90 interval between successive blanks. 100
44. A machine for use in making wire-bound boxes comprising, in combination, co-operating blank-feeding and wiring and fastener-setting instrumentalities, and operating means therefor, said elements constructed and arranged to provide a continuously-operating organization for wiring successive blanks without stopping the machine, and automatic work-controlled means including a work-engaging controller for 105 interrupting the fastener-setting operation.
45. A machine for use in making wire-bound boxes comprising, in combination, fastener-setting mechanism to secure binding wire to the box materials; means 115 whereby the box materials are progressively subjected to the operation of said mechanism; said elements constructed and arranged to provide a continuously operating organization for wiring an indefinite succession of assemblies of box parts; automatic fastener-setting interrupting means; and means controlled by the relative progression between the work and fastener-setting mechanism, including a work-engaging controller, for operating said interrupting means. 120
46. A machine for use in making wire-bound boxes comprising, in combination,

- fastener-setting mechanism to secure binding wire to the box material; means whereby the box materials are progressively subjected to the operation of said mechanism; 5 and fastener-setting interrupting mechanism including actuating means controlled by relative progression between the work and fastener-setting mechanism and means actuated by a given plurality of operations of 10 said actuating means for effecting such interruption.
47. A machine for use in making wire-bound boxes comprising, in combination, fastener-setting mechanism to secure binding wire to the box materials; means whereby the box materials are progressively subjected to the operation of said mechanism; and mechanism for interrupting the fastener-setting operation including controlling 15 means engaging and laterally displaceable by the work and means actuated by lateral displacement of said controlling means for effecting such interruption.
48. A machine for use in making a sectional wirebound box comprising, in combination, means for fastening together the assembled cleats and side material of a box section; means for assembling a plurality of such sections in position for wiring; and 20 means for wiring them together.
49. A machine for use in making a sectional wirebound box comprising, in combination, means for fastening together assembled cleats and side material of a box section; means for presenting fastened sections in succession to a mechanism for wiring them together and operating to crowd together the sections being wired; and mechanism for wiring said sections. 25
50. A machine for use in making wire-bound boxes comprising, in combination, mechanism to secure binding wire to box sections; means to deliver box sections thereto; means for preliminarily relatively positioning cleats and sheet material for a box section preparatory to such delivery; and means for fastening the sheet material to the cleats while so preliminarily positioned. 30
51. A machine of the class described comprising, in combination, work-feeding means to receive successively introduced box sections; mechanism operable upon sections successively for connecting them by binding wires; said work-feeding means constructed 35 and arranged to bring sections into foldable relationship for such connection; means for relatively positioning cleats and side material for a section in position for introduction to said work-feeding means; and means for preliminarily fastening said side material and cleats together while so positioned. 60
52. A machine of the class described comprising, in combination, work-feeding means to receive successively introduced box sections; mechanism operable upon sections 65 successively for connecting them by binding wires; said work-feeding means constructed and arranged for yieldingly advancing following sections at a relatively faster rate than the immediate section being wired; means for relatively positioning cleats and side material for a section in position for introduction to said work-feeding means; and means for preliminarily fastening said side material and cleats while so positioned. 70
53. A machine of the class described comprising, in combination, means for preliminarily fastening together assembled side material and cleats for a box section; means determining assembled relationship of said parts during such preliminary fastening operation; means constructed and arranged to receive said box section and advance it into foldable relationship with a previous section; and mechanism for foldably connecting said sections by binding wires. 75
54. A machine for making sectional wire-bound box blanks comprising, in combination, a plurality of fastener-setting mechanisms arranged to operate at different points 80 in the path of travel of box sections; the first said mechanism adapted for preliminarily fastening together the side material and cleats of a section subjected thereto; the second said mechanism adapted to secure binding wire to a section subjected thereto; means for determining assembled relationship of the parts of a section while subjected to the operation of said first mechanism; and means for moving sections after passing 85 from said first mechanism into foldable relationship for operation of the second mechanism to foldably connect them. 90
